(57) CLAIM

The ornamental design for a phone case with lip balm holder, as shown and described.

DESCRIPTION

FIG. 1 is a top-front-left perspective view of a phone case with lip balm holder showing my new design;

FIG. 2 is a bottom-front-left perspective view thereof;

FIG. 3 is a top-rear-right perspective view thereof;

FIG. 4 is a bottom-rear-right perspective view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is a right elevational view thereof;

FIG. 10 is a left elevational view thereof;

FIG. 11 is a vertical cross-sectional view thereof taken along line 11-11 in FIG. 6;

FIG. 12 is a top-front-left perspective view thereof wherein the phone case with lip balm holder is shown with an environmental lip balm;

FIG. 13 is a top-front-left perspective view thereof wherein the environmental lip balm is shown within the lip balm holder portion of the phone case; and,

FIG. 14 is a top-rear-right perspective view thereof.

The broken lines showing the phone case interior in FIGS. 1-2, 5, and 11-13, and the broken lines showing a lip balm in FIGS. 12-14 are included for the purpose of illustrating environmental structure that forms no part of the claimed design.

1 Claim, 14 Drawing Sheets
